SEALING LIQUID AND PROCESS OF MAKING
SAMEWilliam A. Gruse, Wilkinsburg, Pa., assignor to
Gulf Refining Company, Pittsburgh, Pa., a cor-
poration of Texas

Application July 29, 1932, Serial No. 626,180

17 Claims. (Cl. 196—149)

This invention relates to sealing liquids and processes of making same; and it comprises a particular distilled petroleum oil adapted for use as a sealing liquid, for example, in waterless gas holders, said oil being characterized by a specific gravity somewhat greater than water, by a viscosity about that of a medium-heavy engine lubricating oil, by fluidity at low temperatures, by a flash point not less than 300° F., and by very low tendency to emulsify with, or otherwise carry water, said oil usually being derived from a heavy residual tar resulting from the cracking or so-called "reforming" of petroleum naphtha; and it also comprises a method of making such an oil wherein a heavy residual tar produced in cracking and re-forming a light distillate such as naphtha, is reduced by distillation to about half its original volume, the residue being then blended with a viscosity reducing material, or the last mentioned residue is further distilled, usually under non-cracking conditions, to produce various distillates, one such distillate having the desired properties being produced during such distillation; all as more fully hereinafter set forth and as claimed.

In the last few years the so-called "waterless" gas holders have been gaining favor at the expense of older types, such as the floating bell type or other types in which water or other liquid is displaced by gas. The waterless gas holder comprises a shell or casing surmounted by a roof and containing a movable diaphragm or "piston". The gas is introduced beneath the piston which latter rises and falls with the introduction and withdrawal of gas. A gas-tight seal between the shell and the piston is, of course, a necessity and to secure this a peripheral gutter or trough, kept supplied with sealing liquid, is provided on the piston. A so-called rubbing plate, mounted on the piston, is held pressed against the walls of the holder and a strip of canvas makes a flexible connection between this rubbing plate and the outer edge of the peripheral gutter. The gutter is kept filled with a sealing liquid, the level of which is maintained some distance above the top of the rubbing plate and canvas strip. The sealing liquid forms the actual seal. This liquid drains downwardly between the rubbing plate and the side of the holder to some extent. Water condenses on the inner wall of the holder and gets mixed with the sealing liquid. By making the sealing liquid heavier than water it is possible to conveniently and automatically separate the condensed water from the sealing liquid and also keep water from accumulating in the gutter.

and rotting the canvas. The sealing liquid must also be substantially insoluble in water and not readily emulsifiable. With a heavy liquid of this character, any rain water, etc. gaining access to the top of the gas holder floats on the seal and can be drawn off by extremely simple and automatic means.

The selection of a suitable sealing liquid presents many difficulties and no wholly satisfactory solution of the problem has in the past been attained. Water alone is unsatisfactory in that it causes rotting of canvas and rusting of metal. If it should freeze and so secure the piston to the holder rolls, total destruction might result. Coal tar and various heavy coal tar distillates have been tried. Straight coal tar and straight coal tar distillates have a tendency to emulsify with water and are lost in considerable quantity in the condensed water which is drawn off and discarded; and they have many other impractical aspects.

A liquid suitable for use in the seal should be of a specific gravity greater than that of water; be capable of flowing at all ordinary atmospheric temperatures and advantageously at temperatures as low as, say, —20° F.; be substantially free from any unsaturated hydrocarbons and volatile compounds which can be absorbed by the gas and give a low flash point; be inert to air and gas; and it should not emulsify with water or with drip oil from the gas; it should not deposit sludge in use with water gas or coal gas and it should not dissolve more than 1 per cent of water.

Ordinary commercial oils made from petroleum do not possess the combination of characteristics required. In particular, it is difficult to find any oil of high specific gravity with a sufficient fluidity at low temperatures. Ordinary cracking still tars are useless for this purpose.

I have found, however, that a drastic cracking of certain light petroleum oils such as naphtha tends to give residual tar products of high specific gravity and low viscosity and that certain of such tars can be used as raw material for production of excellent sealing liquids. By "drastic cracking" in this connection I mean subjection to extremely high temperatures, temperatures above 900° to 925° F., for example.

The degree of cracking to which a given petroleum oil can be subjected in commercial operation is that which it will stand without excessive coke deposition, and most petroleum oils cracked at high temperatures produce tars carrying an excessive amount of solid material.

These tars give distillates of unstable character, even light distillates from them sometimes hardening at ordinary temperatures.

In general it is necessary to reduce pressure still or other cracking still tars by 30 per cent or more of their volume before the specific gravities of their distillates exceed that of water. After such a reduction most such tars become solid and their distillates possess excessive viscosities. I have found, however, that conditions are somewhat different in the case of tars produced by a drastic cracking of low boiling petroleum distillates such as naphtha, kerosene and gasoline stocks; as in the operation commonly known as re-forming. I have found that extremely desirable distillates for the present purpose can be recovered from these reforming-still tars. The tars produced in this particular cracking are characterized by high fluidity, by heavy gravity for a given boiling point range, by chemical and physical stability, and by freedom from constituents which become solid and separate out at ordinary temperatures.

In a specific embodiment of the present invention making a sealing oil suitable for the described purposes, I took 100 parts of a tar from a pressure still in which naphtha had been subjected to a temperature of about 950° F. and a pressure of 1500 pounds per square inch. This tar was reduced, or "topped", at atmospheric pressure until 40 parts came over as distillate. This was discarded. At the end of this distillation the temperature had risen to about 600° F. and the specific gravity of the distillate approached 1. The remaining tar was then subjected to vacuum distillation under a pressure of somewhat less than 10 mm. absolute. Fifteen parts of distillate were recovered in a single cut having a specific gravity at 60° F. of 1.001 and a viscosity of 50 seconds S. U. V. at 100° F. Twenty parts more were then recovered as a cut having a specific gravity of 1.05 and a viscosity of 410 seconds S. U. V. at 100° F. The temperature in the still at this point had risen to 516° F. This last cut or a mixture of the last two was suitable for use as sealing liquid.

In methodical operation I usually distil off about 40 to 50 per cent of the original volume from a reforming-still tar, to remove useless low-gravity components. I then distil under reduced pressure, taking a series of 5 per cent cuts until 75 per cent or more of the original charge is distilled off. The distillation temperature is advantageously maintained below about 600° F. to avoid cracking. The 5 per cent cuts recovered in this manner usually range in specific gravity from about 1.0 to 1.05. Their viscosity usually increases towards the end of the distillation to a point somewhat greater than that desired in a sealing liquid. However, the heavier of these 5 per cent cuts are suitable as sealing liquids when blended with sufficient material of low viscosity and high gravity to produce a mixture of suitable viscosity. The lighter and intermediate 65 cuts are usually suitable without such blending. The cuts may be blended among themselves.

The above procedure can be altered to a considerable extent without departing from the scope of my invention. In its broader aspects the process of my invention consists in taking a light petroleum distillate, subjecting said distillate to pressure still cracking conditions at temperatures above 900°-925° F., recovering the (reforming-still) tar produced in said cracking step, distilling this tar, discarding the first dis-

tillate—running about 40 to 50 per cent by volume—because of low density, and then either blending the tar bottoms with a viscosity reducing liquid or continuing distillation under non-cracking conditions until from 40 to 25 per cent of the initial volume remains in the still, and recovering the intermediate fractions. By "non-cracking conditions" I mean that the distillation is conducted under reduced pressure or in the presence of steam or other similarly acting medium.

The secondary tar bottoms remaining after the described removal of 40-50 per cent of the reforming-still tar can be blended with various liquids of high gravity to produce sealing liquids of specific viscosities. Such a viscosity reducing agent for this material may be one of the before-mentioned 5 per cent distillate fractions from another batch or it may be an organic compound. Among such organic compounds there may be mentioned many halogenated compounds such as chlorinated naphthalene ("halowax oils"), chlorinated diphenyls, chlorinated fractions of coal tar oil or pressure still tar, and tributyrin, which latter is the butyric acid ester of glycerol.

Reforming-still tar varies with the conditions of the re-forming operation, but distillates can always be produced with characteristics of the kind indicated by conducting the operation as herein described.

The distillation temperature while producing sealing liquid from reforming-still tar should not rise much above 600° F. If desired the distillate cuts from the tar can be subjected to common refining operations.

For a better understanding of the present invention in the accompanying illustration I have shown in some detail the type of gas holder in which sealing liquids made under the present invention are most advantageously employed. In the illustration there is shown more or less diagrammatically a structure of a waterless gas holder and of the gas seal.

Fig. 1 is a side elevation of a gas holder, part of this showing being in section, while

Fig. 2 is an enlarged sectional view of the gas seal.

In the drawing like elements are designated by like numerals.

The gas holder, as shown in Fig. 1 is formed of an outer shell 1, surmounted by a roof 2. The shell is in the form of a polyhedral prism with 10 to 28 or more vertical sides depending upon the capacity of the holder. The only moving part of the holder is the so-called piston or diaphragm 3. This piston is supported by the gas and by weighting it the gas pressure can be regulated in a simple manner. Around the periphery of the piston are placed two series of radial rollers 4 at different heights, the vertical distance between the two series being about one-tenth of the diameter of the holder. These rollers move along so-called rubbing strips, not shown, as the piston rises or falls.

The structure of the gas seal is shown in section in Fig. 2. Around the periphery of the piston and at the bottom is a trough or "tar cup" 14 which forms the gas seal. The mechanical structure of the seal includes a rubbing plate or bar 5, which at the bottom is attached to the piston proper by a strip of canvas 6. The canvas is attached to the back of the rubbing plate and passes over a wood or metal spacing rod 7 which serves to prevent the canvas from coming into contact with the side of the holder. The canvas

strip 6 is attached to the piston 3 by means of a wooden strip 8 which is bolted to a peripheral flange 8.

The rubbing plate is usually made of metal sufficiently thin and flexible to accommodate itself to any slight irregularities in the surface and is kept pressed against the side of the holder by a lever 10, mounted on the piston, this being pivoted at 11 and weighted at 12. The trough-like depression 14 formed between the side of the holder and the piston is filled with a sealing fluid 13 which serves to prevent the escape of gas. There is always a slight leakage of the sealing liquid past the joint formed between the rubbing plate and the side of the holder. This liquid is recovered in a sump 15 at the bottom of the holder, water is separated therefrom by gravity and the liquid is then pumped back into the trough. The level of the liquid in the trough is generally kept constant by automatic means connected to the sealing liquid pump. It is desirable to employ a sealing liquid having at least some lubricating properties in order to keep the joint between the holder and the rubbing plate lubricated.

The sealing liquid produced by the process hereinbefore described unites the properties desired in such a liquid in high degree. The product of my invention is a distillate having a specific gravity above 1.000, having a viscosity of not over 700-800 seconds S. U. V. at 100° F., having the characteristics of remaining fluid at temperatures of about 0° F. or lower, having but slight tendency to form emulsions with water, having a flash test of not less than 300° F., having low acidity and sulfur content and having a water content of not substantially over 1 per cent. While these properties make my product especially adapted to the waterless type of gas holder, the same properties make my product suitable for other types of holders as well. For example, a holder of the floating bell type can be supplied with the sealing liquid of the present invention with advantageous results.

As previously stated coal tar and certain coal tar distillates have been tried for the purpose for which my product is intended, but these materials have shortcomings. My product is miscible with these materials and obviously its mixture with any of them would greatly improve their usefulness. Beyond that I find that mixture of my product with these materials substantially lessens their tendency to emulsify. Without limitation to any particular blending material, blending permits production of sealing oils having specific combinations of particular characteristics.

What I claim is:

1. As a sealing liquid for waterless gas holders, a pressure still tar distillate obtained by the fractional distillation of the residual tar from the cracking of a low boiling petroleum oil having a specific gravity greater than that of water and a viscosity of the order of that of medium and heavy engine lubricating oils.

2. A gas holder sealing oil produced from the residual tar of a naphtha cracking process having a specific gravity of approximately 1.01 to 1.05, a viscosity at 100° F. on the Saybolt universal viscosimeter of from 200 to 700 seconds, a flash point of not less than 300° F., and being substantially fluid at low temperatures.

3. As a sealing liquid for waterless gas holders, a naphtha cracking still tar distillate char-

acterized by a specific gravity greater than that of water, a viscosity at 100° F. of the order of medium and heavy engine lubricating oils, having low sulfur content and acidity, having a water content of less than 1 per cent and having no strong tendency to emulsify with water.

4. As a new composition of matter, a blend of a pressure still tar distillate obtained by the fractional distillation of the residual tar from the cracking of a low boiling petroleum oil and a coal tar oil.

5. As a new composition of matter, a blend of the tar distillate of claim 3 with a coal tar oil.

6. In the manufacture of sealing liquids for waterless gas holders, the process which comprises subjecting a low boiling petroleum distillate to drastic cracking, recovering the tar formed during said cracking step, reducing said tar to a residuum by distilling off a substantial proportion, further distilling said residuum under non-cracking conditions and recovering a distillate having a specific gravity greater than 1.

7. The process of claim 6 in which the low boiling distillate employed is naphtha.

8. The process of claim 6 in which from 40 to 50 per cent of the tar is distilled off to produce said residuum.

9. The process of claim 6 in which said residuum is distilled under reduced pressure.

10. The process of claim 6 in which the temperature of the distillation steps is maintained below 600° F.

11. In the manufacture of sealing liquids for waterless gas holders, the process which comprises distilling a tar from a naphtha cracking still and recovering a fraction having a specific gravity greater than 1 and a viscosity of the order of that of medium and heavy engine oils.

12. In the manufacture of sealing liquids for waterless gas holders, the process which comprises drastically cracking a low boiling petroleum distillate, recovering the tar formed during said cracking, distilling said tar and recovering a fraction having a specific gravity greater than 1 and having the property of remaining fluid at low temperatures.

13. The process of claim 12 in which the tar is distilled under non-cracking conditions.

14. In the manufacture of sealing liquids for waterless gas holders, the process which comprises distilling a tar from a naphtha cracking still, rejecting a fraction lighter than water and recovering a fraction heavier than water.

15. In the manufacture of sealing liquids for waterless gas holders, the process which comprises reducing a tar from a naphtha cracking still to a residuum representing from 50 to 60 per cent by weight of the original tar, subjecting said residuum to vacuum distillation and recovering a fraction having a specific gravity greater than 1.

16. As a sealing liquid for gas holders, a reduced, re-forming still tar obtained from the cracking of a low boiling petroleum distillate diluted with an organic viscosity reducing liquid having a high gravity.

17. In the manufacture of sealing liquids for gas holders, the process which comprises reducing a re-forming still tar obtained from the cracking of a low boiling petroleum distillate and diluting the bottoms with a viscosity reducing liquid having a high gravity.

WILLIAM A. GRUSE.
